UNITED STATES PATENT OFFICE.

FRANKLIN W. CHAPIN, OF ATHOL, MASSACHUSETTS, ASSIGNOR OF ONE-HALF TO
WILLIE L. GERHARD, OF ATHOL, MASSACHUSETTS.

GAME.

Application filed July 14, 1924. Serial No. 725,916.

To all whom it may concern:

Be it known that I, FRANKLIN W. CHAPIN, a citizen of the United States, residing at Athol, in the county of Worcester and State 5 of Massachusetts, have invented certain new and useful Improvements in Games, of which the following is a specification.

This invention relates to a device that may be broadly classified as a new game, but the 10 invention has more particular reference to a device of this class which may be more conveniently termed a puzzle.

In carrying out the present invention, I have evolved and produced what I believe 15 to be an exceedingly novel little toy, which will undoubtedly provoke considerable amusement, both for children and grown up persons.

Broadly speaking, the improved toy comprises a container which is divided by internal partitions into a multiplicity of passageways for a plurality of gravity rolled balls which will pass through the passageways at random when the container is tilted 20 into various positions. The container is provided with a pocket or a pen which is the goal sought, it being the object of the players to attempt to collect all of the balls within this pen.

It is a feature of the invention to practically conceal all of the so-called passageways, so that the players will be unable to ascertain in which passageway the balls are contained after the container is first tilted. 30

It is also a feature and an advantage of the invention to so arrange certain of the passageways that a skilled performer may, by proper manipulation, collect substantially all of the balls in a pocket in a very short time. 35

It is another, but no less important feature of my invention to provide a comparatively simple and inexpensive device of this class, which may be sold for a paltry sum. 40

Other features and advantages of the invention will become apparent from the following description and drawings. 45

In the accompanying drawings, forming a part of this application, and in which like numerals are employed to designate like parts throughout the same: 50

Figure 1 shows a top plan view of a puzzle, constructed in accordance with the present invention.

Figure 2 is a transverse section, taken sub-

stantially on the plane of the line 2—2 of 55 Figure 1.

The preferred embodiment of the invention comprises a comparatively shallow box 1 of suitable material. The box is preferably elongated or substantially rectangular in 60 configuration. As before stated, I propose to divide this box internally, through the use of a multiplicity of partitions, into a plurality of passages or passageways for the gravity rolled balls 2. Of course, this end may be accomplished in other ways, but I prefer to employ a plurality of blocks which may be wooden blocks if desired. Furthermore, if the box 1 is composed of cardboard as I contemplate, these blocks may be simply 65 glued in their proper relative positions. The blocks are of various sizes and designs and are accurately arranged to provide rather tortuous passageways. For instance, I may use a comparatively large double notched block 3 in the forward left hand corner, with a row of substantially symmetrical oblong spaced blocks 4, at the same end of the box. Cooperative with the blocks 4 and 3 is an elongated oblong block 5, which is spaced 70 from the first named oblong and adjacent the block 5 is a substantially square block 6, next to which is an L-shaped block 7. A larger and similar shaped block 8 is disposed in spaced but close proximity to the 75 block 7. The before-mentioned pen or pocket is designated by the reference character 9 and this is formed by the elongated boundary walls 10. The entrance to this pen is indicated at 11. It will be noted that the 80 wall of the entrance is directed in a diagonal direction as seen. Also, to frustrate the entrance of the balls into the pocket or pen, internal blocks 12 are provided. In addition to these other obstruction or partition 85 blocks are provided, but these need not be referred to, it being only essential that the blocks be of a shape and design and so arranged as to provide a multiplicity of tortuous passages which are in communication 90 with the entrance to the pockets. 95

As before stated, the double passageways are concealed from view, and in carrying this out, I simply propose to place a cardboard diaphragm over the passages, this diaphragm being more clearly shown in Figure 2, and being represented by the reference character 13. It is to be noted that the dia- 100 105

phragm terminates in spaced relation from one end of the box and serves to uncover one end of the aforesaid pen. In order however, to prevent the balls from getting out 5 of the box, a glass cover 14 is placed entirely over the open side of the box. This cover enables the balls to be seen only in the inner end of the container.

In playing the game, the five little balls 10 are gathered in one or the other of the corners of the box, as shown in Figure 1, and the latter is lifted and tilted back and forth, in an attempt to collect all of the balls in the pen. As soon as the box is tilted, the 15 balls run helter skelter and at random, all over the box, under the influence of gravity, and it is exceedingly difficult to gather all five balls in the pocket. By proper manipulation, however, it is possible to collect all 20 five of the balls in the pocket. For instance, a very skilled player may cause the balls to slowly follow each other in succession in a predetermined and known course, thus following the least obstructed path to said 25 pocket. Comparative skill, however, is required to do this, and it is in view of the difficulty of winning that a high degree of amusement is provided. It is thought that persons skilled in the art to which the 30 invention relates may be able to obtain a clear understanding of the same from the foregoing description and drawings. Therefore, a more lengthy description is deemed unnecessary.

35 Although I have shown and described a specific embodiment of the invention, it is to be understood that minor changes coming within the scope of the adjoined claims may be resorted to, if desired.

40 I claim:

1. A container provided with a multiplic-

ity of tortuous ball passages, non-transparent means disposed over and concealing said passages, a plurality of gravity influenced balls in said container adapted to travel through said passages, and a ball collecting pocket having a restricted inlet in communication with but two of said passages.

2. A game of the class described comprising 50 a container, a plurality of blocks arranged in spaced predetermined positions in said container for dividing it into a multiplicity of passageways, a ball collecting pocket in said container, a non-transparent 55 diaphragm covering said passageways to conceal them, said diaphragms terminating in spaced relation from one end of the pocket and container, a plurality of balls in said container adapted to travel through 60 said passageways and into said pocket, and a glass cover for said container, said cover exposing a portion of the pocket and said balls when they are in a predetermined position.

3. A game of the class described comprising 65 a container, a plurality of obstructions arranged in spaced predetermined positions in said container for dividing it into a multiplicity of passageways, certain of said 70 passageways communicating with each other and other passageways being out of communication with each other, a ball collecting pocket in said container, said pocket embodying a restricted inlet for the balls, on 75 one side of which is a diagonally disposed wall, obstructions within said pockets tending to hinder the entrance of balls, and a closure for said container.

In testimony whereof I affix my signature.

FRANKLIN W. CHAPIN.
